APPARATUS FOR COOLING

John C. Lincoln, Cleveland, Ohio

Application May 29, 1934, Serial No. 728,160

7 Claims. (Cl. 62—139)

This invention relates as indicated to a method of and apparatus for cooling and pertains more specifically to a method of and apparatus for cooling a stream of air which, after being thus cooled, may be caused to circulate into or through a building or the like in order to reduce the temperature within such room or building.

It is a principal object of my invention to provide a method and apparatus of the above described character characterized by its simplicity of construction and low cost of operation.

It is a further and more particular object of my invention to provide a method of and apparatus for cooling wherein the temperature of a membrane is reduced to substantially wet bulb temperature by maintaining on one surface thereof a film of water which is evaporated by the passage of a current of air thereover. The air to be cooled is then brought into contact with such cooled membrane.

Other objects of my invention will appear as the description proceeds.

To the accomplishment of the foregoing and related ends, said invention, then, consists of the means hereinafter fully described and particularly pointed out in the claims, the annexed drawing and the following description setting forth in detail certain means and one mode of carrying out the invention, such disclosed means and mode illustrating, however, but one of various ways in which the principle of the invention may be used.

In said annexed drawing:—

Fig. 1 is a vertical, part sectional, part elevational view of one form of apparatus constructed in accordance with the principles of my invention; Fig. 2 is a vertical sectional view through the apparatus illustrated in Fig. 1 taken on a plane substantially indicated by the line 2—2; Fig. 3 is a fragmentary sectional view drawn to an enlarged scale of a part of the apparatus illustrated in the previous figures taken on a plane substantially indicated by line 3—3 on Fig. 1; Fig. 4 is a fragmentary perspective view of the upper end of a portion of the apparatus illustrated in Figs. 1 and 2 and illustrating more particularly the arrangement of the means for distributing a film of water over certain faces of the vertically disposed partitions or membranes; and Fig. 5 is a fragmentary perspective view showing more particularly the construction of one form of the membrane or partition members illustrated in the previous figures.

Referring now more specifically to the drawing and more especially to Figs. 1 and 2, the appa-

ratus herein illustrated and by which the principles of my invention may be carried on consists of a substantially rectangular vertically disposed frame generally indicated at 1. Mounted within the rectangular frame 1 and supported therein in the manner hereinafter more fully explained are a plurality of membranes generally indicated at 2. These membranes or vertically disposed partition members which are arranged in spaced relation are preferably formed of some suitable material such as thin copper or aluminum sheet or celluloid, cellophane, vegetable parchment or the like. The particular requirement for the membranes 2 is that they be impervious to water, of good thermal conductivity and sufficiently thin so as to readily and quickly transmit heat therethrough. In other words, the membranes 2 are preferably of some material which provides an effective supporting surface for the film of water but which will not permit the passage of water therethrough, and efficiently transfer the heat from the air contacting the dry side of the membrane to the film of water being evaporated from the opposite side thereof.

As illustrated in Figs. 4 and 5, the membranes 2 are shown tacked or similarly secured at their vertical edges to strips such as 3 which may be of wood or other suitable material. The vertically disposed strips 3 to which the membranes 2 are secured are slightly wedge-shaped in their vertical extent for the reason hereinafter more fully explained.

After the membranes 2 are secured in pairs to the strips 3, as shown in Fig. 4, they are positioned within the vertically disposed and laterally substantially completely closed frame 1 and are supported therein by means of screws 4 which are preferably, at their inner ends, secured to the strips 3; then extend outwardly through slightly enlarged openings in the wall of the enclosing casing 1. The screws 4 are provided with enlarged heads to serve as an abutment for springs 5 which, at their opposite ends, may abut against the outer surface of the frame 1.

Screws such as 4 are positioned on opposite sides of the partition members comprising the membranes 2 and strips 3 so that the effect of the springs 5 is to maintain the membranes 2 in a taut condition.

Should the surface of the membranes 2 be of an oily nature, thereby not conducive to maintenance thereover of a continuous film of water, one face, i. e., that which is to carry such film, may be provided with an adherent coating or

layer of water absorbent material 6 which may be of felt, cheesecloth, filter paper or the like.

Extending along one side of the frame 1, near the upper edge of the membranes 2, is a header 7 from which extend a plurality of water pipes 8. The water pipes 8 are arranged in the alternate spaces defined by the upper ends of the membranes 2 so that the water projected therefrom will wet one side only of all of the membranes.

As most clearly illustrated in Figs. 3 and 4, some means such as felt wicks 9 may be provided adjacent the upper edges of the membranes 2 so as to evenly distribute over such membranes the water which is projected from the pipes 8. The wicks 9 may be suitably supported in position by some means such as a saddle 10 formed of foraminous material and welded to or similarly secured to the pipe 8 and/or the membranes 2.

The effect of the wicks 9 is to feed the water from the supply pipes at a uniform rate to the surfaces of the membranes and also to evenly distribute the water throughout the entire transverse extent of such membrane surfaces which might not occur if the water were projected against the membranes by spaced streams issuing from the pipes 8.

Positioned beneath the frame 1 and the previously described assembly contained therein is a catch basin generally indicated at 11. The spaces between the wet faces of the membranes are open at the bottom so that any moisture remaining on such membranes and dripping from the bottom edges thereof will be caught in such catch basin. A pump 12 which may be of any suitable form and actuated by means of a plunger rod 13, operated from a cam 14, driven by a motor 15, is employed to elevate water from the catch basin 11 through the pipe 16 which is then forced through the pipes 8 and discharged against the membranes 2 in the manner hereinbefore described.

The spaces between the dry faces of the membranes are closed at the bottom by members such as 17. The left side wall, as viewed in Fig. 1 of the rectangular frame 1, is cut away in the areas generally indicated at 18 and a suitable header 19 is provided for the purpose of collecting the air which issues from the openings 18.

The rectangular frame 1 is, at its upper end, provided with an opening 20 in which may be positioned a fan 21 for the purpose of forcing streams of air downwardly through the vertical spaces defined by the membranes 2.

The operation of the foregoing apparatus may be briefly described as follows:—

Energization of the motor 15 will result in the energization of the pump 12 and the fan 21. The pump 12 will force water from the catch basin 11 through the pipes 8 so as to maintain a film of moisture on one side only of each of the membranes 2. The fan 21 will cause divided streams of air to flow downwardly through the spaces laterally defined by the wet and dry faces respectively of the membranes, i. e., the air which passes downwardly through the spaces 22 will be in contact with the water film on the surfaces of the membranes defining such spaces. The wedge-shape of the members 3 slightly inclines the membranes so as to facilitate the maintenance of a uniform film of moisture over the face of the membranes. The air which passes downwardly through the spaces 23 is in contact with the dry faces of the membranes. The evapora-

tion of the water from the wet faces of the membranes will reduce the temperature of such membranes to substantially wet bulb temperature so that the dry air in the spaces 23, by the time it issues from the openings 18 and the header 19, will also be reduced to substantially wet bulb temperature, i. e., from 10 to 30° F. lower than the temperature at which it was admitted to the cooler by means of the fan 21.

The air which passes downwardly through the spaces 22 is discharged to the outside over the surface of the water in the catch basin 11. The dry air which has passed downwardly through the spaces 23 and has become cooled is discharged from the header 19 into the room or building to be cooled.

In view of the fact that a certain percentage of the water projected from the pipes 8 onto the surfaces of the membranes is evaporated in order to accomplish the cooling, some means must be provided for maintaining a constant supply of water in the catch basin 11. Any suitable means of supply may be provided for this purpose. It is, of course, possible to connect the pipes 8 directly to the source of supply and then dispense with the pump 12. The re-circulation of the water effected by the pump 12, of course, results in a material saving, inasmuch as all the water not evaporated is re-circulated.

It is believed that the construction and operation of the apparatus by which the principles of my invention may be practiced may be understood without a further description, it being noted that the form of the apparatus may be materially changed without departing from the principles of my invention.

As previously indicated, the fundamental concept is the depositing of a layer or film of air on a membrane, evaporating such film by the passage of a current of air thereover, which evaporation results in a reduction in temperature of the membrane, and then circulating the air to be cooled in contact with the dry face of the membrane so that the cooled air will be reduced in temperature without picking up any moisture.

Other modes of applying the principle of my invention may be employed instead of the one explained, change being made as regards the means and the steps herein disclosed, provided those stated by any of the following claims or their equivalent be employed.

I, therefore, particularly point out and distinctly claim as my invention:—

1. In an apparatus for cooling, a relatively thin membrane of vegetable parchment, means for applying a film of water to one side of said membrane, means for passing a stream of air over said film to evaporate at least a part thereof and thus reduce the temperature of said membrane, and means for passing the stream of air to be cooled over the dry surface of said membrane thus cooled.

2. In an apparatus for cooling, a relatively thin membrane of vegetable parchment, a layer of water absorbent material on one side of said membrane, means for wetting said layer of absorbent material, means for supplying separate streams of air respectively over the wet and dry sides of said membrane, and means directing said last named stream to the space to be cooled.

3. In apparatus of the character described, the combination of a thin, water-impervious membrane, a water distributing wick member on one vertical face of said membrane and extending

transversely thereof adjacent its upper end, spray means for supplying water to said wick member, and means for supplying separate streams of air respectively over opposite sides of said membrane.

5 4. In apparatus for cooling, a substantially non-porous relatively thin non-metallic membrane, means for supplying a film of water to one side of said membrane, means for passing streams of air respectively over the opposite sides of said membrane, and means for maintaining said membrane in a taut condition.

10 5. In apparatus for cooling, a relatively thin membrane of vegetable parchment, means for supplying a film of water to one side of said membrane, means for passing streams of air respectively over the opposite sides of said membrane, and means for maintaining said membrane in a taut condition.

15 6. In an apparatus for cooling, a substantially

non-porous relatively thin non-metallic membrane, means for applying a film of water to one side of said membrane, means for passing a stream of air over said film to evaporate at least a part thereof and thus reduce the temperature of said membrane, and means for passing the stream of air to be cooled over the dry surface of said membrane thus cooled.

7. In apparatus of the character described, a combination of a thin water impervious membrane, a water distributing wick member on one vertical face of said membrane and extending transversely thereof adjacent its upper end, means for supplying water to said wick member, a layer of water absorbent material on one side of said membrane below said wick member and means for supplying separate streams of air respectively over opposite sides of said membrane.

JOHN C. LINCOLN.
